DERAIL DEVICE

William K. Wilbur, Pittsburgh, Pa., assignor to
Portable Lamp & Equipment Company, Pitts-
burgh, Pa., a corporation of Pennsylvania

Application March 28, 1936, Serial No. 71,463

3 Claims. (Cl. 246—163)

The present invention relates to a derail device which is particularly adapted for location at a desired point along a track rail, and can be moved from point to point easily. Devices of 5 this type are advantageous in railways which are shifted from time to time, as in mines and at industrial works.

One of the features of the present invention is the provision of a derail comprising a structure 10 fixed relative to the rail, and a pivoted structure which may be swung into position above the rail or which may be displaced therefrom to permit free passage of a car, the movable part being located outside of the rail when in non- 15 operative position, so that it may be easily and quickly swung toward operative position by a workman without this workman being obliged to move any portion of his body over the rail.

Another feature of the present invention is the provision of a derail device comprising a wheel- 20 receiving ramp with a guide wall for causing the wheel to be deflected relatively outward in derailing, in association with a further guide 25 member for preventing the wheel returning onto the rail.

A further feature of the invention is the provision of a derail structure having ramp means 30 for receiving the wheel whereby to cause the wheel flange to be elevated above the top of the rail, with guide means for deflecting the wheel outwardly relative to the rail and inclined on the 35 derail structure for causing the weight of the car to determine a continued outward movement of the wheel after it has left the guide means.

With these and other features as objects in view, as will appear in the course of the following specification and claims, an illustrative form 40 of practicing the invention is shown on the accompanying drawings, in which:

Figure 1 is a top plan view of the derail structure in its operative position on a rail.

Figure 2 is a side elevation of the same from the outer side of the rail.

Figure 3 is an end elevation of the same, showing the car rail in position raised above the track rail.

Figure 4 is an upright transverse section substantially on line 4—4 of Fig. 1, showing the car wheel on the inclined discharging surface.

Figure 5 is a plan view of the fixed or base block with portions of the rail being shown in section.

Figure 6 is an end elevation corresponding to

that of Fig. 4, but with the movable block in non-operative position.

In these drawings, the derail device is illustrated as comprised of a base block or member B, a pivot pin P, and a movable member or rocking block R; this assembly being held in position by a wooden wedge W.

The base member comprises a floor portion 10 which is received against the base of the rail (Figs. 3, 4 and 5) and is provided at the inner 10 face of the rail with the upwardly and inwardly extending lug structure 11 for engaging over the inner flange of the rail foot. This floor is stiffened by the flanges 10a, 10b which extend over the structure 11 to reinforce the base member 15 beneath and at the inner side of the rail. At the outer side of the rail, the base block B is provided with an upstanding structure comprised of a smooth wall 12 extending from end to end and having the outwardly projecting ribs 13 constituting pilasters or webs for stiffening the up- 20 standing structure. At the top of the wall 12 and pilasters 13 are provided integral inwardly extending noses 14 which provide ledges for engaging the wedge block. The upper surfaces 14a 25 of these noses are preferably inclined downwardly and inwardly at a small angle (Figs. 3 and 6). The two inner noses 14 are stiffened by a substantially horizontal web 15, and the corresponding inner pilasters are joined by an 30 upstanding rib 16, so that the structures are stiffened and adapted for the employments as described hereinafter. The wall 12 is cut away adjacent the outer pilasters 13 (Fig. 2) for receiving the ears 20 of the rocking block R. 35

The pivot pin P is illustrated as formed by a threadless bolt having a hole adjacent its end for receiving the cotter pin CP.

The rocking block R is made substantially symmetrical about an upright transverse plane. 40 At each end, it is provided with a ramp portion 21 which in operative position rests upon the top of the track rail TR (Figs. 3 and 4), and has its inner face closely in alignment with the corresponding inner face of the track rail TR. 45 Each end of the rocker block also has a wall 22 extending horizontally from the ramp portion 21 at a low level compared with the upper surface thereof; and preferably the vertical spacing between the upper surfaces of the ramp 50 member 21 and the horizontal wall 22 is such (Fig. 3) that the wheel flange does not ride upon this wall 22, while the wheel is riding up on the ramp 21. At the outer edge of the horizontal wall 22, is provided the guide wall 23 which 55

is inclined relatively outwardly and has a slightly curved portion at its immediate length constituting a transition to the corresponding guide wall 23 at the other end of the structure. Further, the outer face of the guide wall 23 is inclined downwardly and outwardly to provide a better engagement for the inner face of the car wheel flange. The upper surface of wall 22 rises (dotted lines, right-hand end, Fig. 2) to the floor level 25 which extends substantially horizontally for a distance between the adjacent ends of the ramp members 21. At the outward portion of the rocker block R, this floor is joined by a downwardly and outwardly inclined surface 26 which extends substantially at the level of the top of the rib member 16 at its lower margin. This inclined surface 26 is cut away centrally to permit the rocker block R to be rocked between operative and inoperative positions without interference by the rib 16, thus providing the spacing between the ears 20.

It will be noted (Fig. 1) that the two guide walls 23 provide a guide portion which in horizontal plan has the form of a broad V, and generally that the structure is essentially symmetrical about a transverse plane substantially at the point designated by the reference line 4—4.

The adjacent ends of the ramp members 21 are brought to a substantial point, the surface 21a of each being curved slightly toward parallelism with the guide member 23 to afford ample clearance for the flanges of the car wheel; and the other side 21b being given a greater curvature so that the nose 21c is relatively inward of the central point of the V-shaped guide structure 23—23 and hence of the position assumed by a car wheel which has been deflected by the guide wall or member 23 at the other end of the device, thus operating to prevent re-railing of the wheel.

At the lower side of the rocker block R, it is provided with flange portions 30 extending from end to end of the ramp members 21 and engageable with the outer face of the rail to prevent twisting about a vertical axis upon impact of the car wheel with the rocker block; and also to confer strength and stiffness against forces operating vertically, and operates in conjunction with the guide walls or portions 23 for this purpose. This flange 30 is joined by small stiffening flanges 31 which connect also with the ears 20.

One of the advantages of the aforesaid arrangement is that the base block B and the rocker block R may each be formed of an integral casting, the several parts cooperating to confer the necessary strength as well as to assure a proper functioning.

In operation, when the device is in the position of Figs. 1—4, ready for the operation of derailing, the wheel CW of an approaching car encounters the ramp member 21 with its tread portion and rises thereon. The flange of the car wheel encounters the relatively high guide wall 23, and thus the wheel as a whole is deflected into the position CW¹ (Fig. 1) and is carried to a position above the top of the track rail TR and then brought down upon the floor 25. This floor is very narrow at the midlength of the illustrated device, so that the flange of this car wheel tends to run downwardly and outwardly along the inclined surface 26, as illustratively shown by the position CW² of this car wheel in Figs. 1, 2 and 4. Normally, with a level rail, the car wheel leaves the rocker block without encountering the surface 21b. However, even in abnormal cases, and

especially when the rail is tilted so that the surface 26 is not presented at a proper incline for the gravitational discharge of the car wheel, the car wheel cannot be re-railed, as its flange engages the surface 21b of the other ramp member 5 which thus operates as a further guide for effecting a definite derailing. The relative position of the nose 21c of this other ramp member assures the definite engagement of the surface 21b with the outside of the car wheel flange. 10

It will be noted that the same action occurs with the car wheel approaching from the other direction. Hence it is possible to locate the present structure on the outer rail of a curve, regardless of the direction in which traffic may be 15 moving.

When it is desired to permit a car or trip of cars to move past the derailing structure, the workman need only grip a projecting wall 22 and lift and swing the rocker block R into the position shown in Fig. 6. For re-engaging the member, the workman grasps the rocker block R in its position of Fig. 6 and gives it an upward and inward swinging movement. It will be noted that the pivot point is such that the workman need 25 not bring his hand, foot or other part of his body to the track gauge line in order to accomplish this; and hence he is protected against accident hazards of being struck or crushed by an approaching car. 30

The device as assembled is placed upon the track rail at a desired point by sliding the floor plate 10 beneath the track rail and engaging the lugs 11 over the inner foot portion of the rail. A wooden wedge W is then driven in from the 35 direction opposite that from which the traffic will normally approach. This wedge is constructed to bear downwardly against the outer foot portion of the track rail TR and upwardly against the noses 14, as indicated by the arrows 40 in Fig. 3; thus operating to draw the floor plate 10 tightly against the bottom of the rail base; and, in addition, the block is constructed to closely fill, and usually to have a slight wedging action, between the web of the track rail TR and 45 the adjacent surface of the upright wall 12.

This base block B, further, is characterized in interchangeably supporting the car stop structure of the copending application of Samuel Clarke, Serial No. 37,406, filed August 22, 1935; 50 and the car skid support as illustrated in Figs. 11 and 12 of the copending application of Charles A. Warden, Serial No. 53,818, filed December 10, 1935; and reference is made to these copending applications as indicating other manners of employing this base member. 55

It is obvious that the invention is not limited solely to the form of construction shown, but that it may be modified in many ways within the scope of the appended claims. 60

I claim:

1. A derail head comprising a flat plate-like body portion adapted to rest upon a rail and having upstanding therefrom a broad V-shaped derailing flange disposed with the base of the V 65 transversely of and laterally-outwardly of the rail center and the legs of the V extended inwardly of the rail, a lift ramp centered on the rail in spaced relation to each V-flange leg and adapted for lifting a wheel flange onto said body portion, the 70 opposed ends of the ramps being definitely spaced from each other and the base of the V-flange to provide well defined intervening horizontal floor portions and upstanding from said flat body portion to constitute rerail preventing means, and 75

means for securing the body portion upon a rail.

2. A derail head comprising a flat plate-like body portion adapted to rest upon a rail and having upstanding therefrom a broad V-shaped derailing flange disposed with the base of the V transversely of and laterally-outwardly of the rail center and the legs of the V extended inwardly of the rail, a lift ramp centered on the rail in spaced relation to each V-flange leg and adapted for lifting a wheel flange onto said body portion, the opposed ends of the ramps being definitely spaced from each other and the base of the V-flange to provide well defined intervening horizontal floor portions and upstanding from said flat body portion to constitute rerail preventing means, said opposed ramp ends each including an outwardly inclined wheel flange deflecting surface and a receiving nose disposed adjacent the innermost edge of the rail, and means for securing the body portion upon a rail.

3. A derail head comprising a plate-like body

portion adapted to rest upon a rail and having upstanding therefrom a broad V-shaped derailing flange disposed with the base of the V transversely of and directed laterally-outwardly and the legs of the V extended inwardly of the rail, a lift ramp 5 centered on the rail in spaced relation to each V-flange leg and adapted for lifting a wheel flange onto said body portion, the opposed ends of the ramps being definitely spaced from each other and the base of the V-flange in a common line 10 disposed parallel the rail center and inwardly of said V-flange base and upstanding from said body portion to constitute rerail preventing means, means for securing the body portion upon a rail including a base having hinge means formed 15 thereon and provision for gripping a rail, and an outwardly and downwardly directed wheel flange guiding portion extending from said body portion carrying hinge means operatively connected with said first-named hinge means. 20
